[57] CLAIM

The ornamental design for a bumper strip for tennis racquets, as shown and described.

DESCRIPTION

FIG. 1 is a perspective view of a bumper strip for tennis racquets showing my new design;

FIG. 2 is a side elevational view thereof, shown in a flat position, the side opposite being a mirror image;

FIG. 3 is a top plan view thereof;

FIG. 4 is a bottom plan view thereof; and

FIG. 5 is an end elevational view thereof.

The tennis racquet shown in broken lines in FIG. 1 is for illustrative purposes only and forms no part of the design.

FIG. 3

FIG. 2

FIG. 1

FIG. 4

FIG. 5
